No. 870,638.

PATENTED NOV. 12, 1907.

G. D. NEILL.
MINER'S CANDLESTICK.
APPLICATION FILED MAR. 4, 1907.

UNITED STATES PATENT OFFICE.

GUY D. NEILL, OF DENVER, COLORADO.

MINER'S CANDLESTICK.

No. 870,638.

Specification of Letters Patent.

Patented Nov. 12, 1907.

Application filed March 4, 1907. Serial No. 360,548.

To all whom it may concern:

Be it known that I, GUY D. NEILL, a citizen of the United States, residing at Denver, in the county of Denver and State of Colorado, have invented certain new and useful Improvements in Miners' Candlesticks, of which the following is a specification.

My invention relates to improvements in miner's candle sticks, its object being to provide an instrument of the class named which combines efficiency and practicability in use with great simplicity of construction and operation and for this reason may be manufactured at a cost which permits it to compete in trade with the ordinary, unimproved miner's candle sticks now in common use. I attain this object by the mechanism illustrated in the accompanying drawings in the various views of which like parts are similarly designated and in which

Figure 1—represents a perspective view of the device ready for use, Fig. 2—a partially sectional plan view of the instrument, Fig. 3—a longitudinal section taken along a line 3—3, Fig. 2, Fig. 4—an underneath view of the device with the parts in the folded position, Fig. 5—an enlarged cross-section taken along a line 5—5, Fig. 2, Fig. 6—an enlarged transverse section along a line 6—6, Fig. 2, and, Fig. 7—a perspective view showing a modified construction of the candle holder.

Referring to the drawings, the reference numeral 5 designates a handle formed of a single piece of spring metal, bent midway its extremities to form a resilient yoke 6, its ends being brought near together to form the normally parallel jaws 7. These jaws are provided at their inner, opposite surfaces with longitudinally and centrally extending, concave grooves 8 which are occupied by the rounded extremity 9 of the entering point, spike or stab 10 which is designed to pierce the wall or other surface, upon which the device is to be secured.

The spike 10 is provided at a distance from the extremity of its rounded portion, with a transverse pin 11, the projecting extremities of which extend rotatably through axially alined, transverse apertures 12 in the jaws 7. When the spike 10 is turned about its pivot at an angle to the handle 5, the jaws 7 spring 45 away from each other, to resume their original position after the stab has been brought in either the folded or unfolded position when, by their tendency to converge, they secure it against displacement.

The reference character 13 indicates the member 50 employed to suspend the device from a projecting point in the wall and consists of a shank 14 having an arcuately curved extremity 15 and a lug 16 projecting laterally at right angles from its opposite end. This lug extends, in practice, within a longitudinally ranging 55 groove 17 in the extreme end of the rounded portion 9 of the spike and is pivotally held in relation thereto

by means of a pin 18 projecting through axially alined openings in the said lug and the bifurcated end of the entering point 10. This construction permits the two members to be folded upon each other and jointly turned to a position within the handle, when the instrument is not in use, as shown in Fig. 4.

To further secure the movable parts of the device against displacement when in the opened position, illustrated in Fig. 1, I have provided a locking means 65 19 consisting of an arm integral with and extending upwardly from one of the jaws 7 and provided at its upper extremity with an inwardly ranging protuberance 20, which when the members are in operative position, occupies a correspondingly shaped indentation 70 in the adjacent side of the hook 14.

It will be observed that by reason of the resiliency of the handle, the locking member 19 and the hook are disengaged when the spike is turned at an angle to the jaws and the latter are, in consequence, further separated.

The candle holder 21 consists of a single flat piece of spring metal which terminates in laterally reduced tongues 22 and 24 respectively alined with its upper and lower edges which when the intermediate, main 80 body of the metal is circularly bent, cross each other in substantially tangential relation to the cylindrical portion 23. One of these tongues 22 is fixedly secured upon the outer surface of one of the jaws 7, by soldering, riveting or analogous means while the opposite tongue 85 24 extending outwardly affords means to readily manipulate the holder when it is desired to distend the cylindrical portion for the purpose of inserting a candle.

In the modified form illustrated in Fig. 7, the candle holder has but one centrally projecting tongue 25, 90 which in practice extends through a corresponding slot 26 in proximity to its opposite end.

As the operation of the instrument has been referred to at intervals, in the foregoing description, further explanation referring to the usage of the device is 95 deemed superfluous.

What I claim as my invention and desire to secure by Letters Patent is:—

1. In a miner's candle stick, the combination of an 100 expansible yoke having normally parallel, longitudinally grooved jaws, and a pair of pivotally connected supporting devices, pivotally positioned within the grooves, the said yoke being adapted to pinchingly retain the said devices in their adjusted positions.

2. In a miner's candle stick, the combination of an 105 expansible yoke having jaws adapted to clamp an interposed object, and a pair of pivotally connected supporting devices, pivotally mounted between the said jaws, the said yoke being adapted to pinchingly retain the said devices in their adjusted positions.

3. In a miner's candle stick, the combination of an 110 expansible yoke having normally parallel, longitudinally grooved jaws, an entering point having a rounded terminal portion normally within the grooves and pivotally mounted between the jaws at a point intermediate its extremities, 115

and a suspending hook, pivotally secured upon the extremity of the said terminal portion, the said yoke being adapted to pinchingly retain the said entering point in its adjusted positions.

5 4. In a miner's candle stick, the combination of a resilient handle having normally parallel, longitudinally grooved jaws, an entering point having a bifurcated terminal portion normally within the grooves and pivotally mounted between the jaws at a point remote from its extremity, and a hook member having a lateral lug pivotally secured upon the bifurcated terminal.

5 5. In a miner's candle stick, the combination of a resilient handle having normally parallel, longitudinally grooved jaws, an entering point pivotally mounted between the jaws, a suspending hook pivotally secured at the inner extremity of the said point, and an arm upon the handle having a protuberance adapted to en-

gage the said hook when the latter is at right angles to the entering point and its pivoted extremity is within the handle.

20

6. In a miner's candle stick the combination of a resilient handle having normally parallel, longitudinally grooved jaws, an entering point pivotally mounted between the jaws, a suspending hook, pivotally secured at the inner extremity of the said point and a locking means upon the handle adapted to frictionally engage the said hook when the latter is at right angles to the entering point and its pivoted extremity is within the handle.

30

In testimony whereof I have affixed my signature in presence of two witnesses.

GUY D. NEILL.
